United States Patent Office

Des. 218,736
Patented Sept. 22, 1970

218,736

HOUSE

Delp Waldo Johnson, 240 Oakview Drive,
San Carlos, Calif. 94070

Filed Oct. 3, 1969, Ser. No. 19,409

Term of patent 14 years

Int. Cl. D25—04

U.S. Cl. D13—1

FIG. 1 is a front elevation of the house of my invention, illustrating the front side wall and overlying roof;

FIG. 2 is a side elevation of the house illustrating the right-hand side wall and overlying roof;

FIG. 3 is a rear elevation illustrating the rear house side wall and overlying roof;

FIG. 4 is a left side elevation illustrating the left-hand side wall and overlying roof; and

FIG. 5 is a plan view of the roof.

I claim:

The ornamental design for a house, as shown and described.
